UNITED STATES PATENT OFFICE.

WILLIAM ALCORN, OF RICHLAND, IOWA, ASSIGNOR OF ONE-HALF OF HIS
RIGHT TO R. HENRY CUTLER, OF SAME PLACE.

IMPROVEMENT IN END-GATES FOR WAGONS.

Specification forming part of Letters Patent No. 222,372, dated December 9, 1879; application filed
October 27, 1879.

To all whom it may concern:

Be it known that I, WILLIAM ALCORN, of Richland, in the county of Keokuk and State of Iowa, have invented certain new and useful Improvements in End-Gates for Wagons; and I do hereby declare that the following is a full, clear, and exact description of the invention, which will enable others skilled in the art to which it appertains to make and use the same, reference being had to the accompanying drawings, which form a part of this specification.

Figure 1 is a perspective view of a wagon-box with my improved end-gate open. Fig. 2 is a side view, the end-gate being closed. Fig. 3 is an end view, and Fig. 4 is a side view, with longitudinal section of the locking-box.

Corresponding parts in the several figures are denoted by like letters of reference.

This invention relates to an improved end-gate and scoop-board for wagons; and it consists in certain improvements in the construction and arrangement of the same, which will be hereinafter fully described, and particularly pointed out in the claim.

In the drawings, A refers to the wagon-box. The end-gate B is hinged to the box by straps C, which permit it to be opened freely, as represented in Fig. 1, and at the same time form braces or supports of great strength.

To the sides of the end-gate are hinged or pivoted segmental braces D D, sliding in boxes E upon the sides of the wagon-box, and provided with notches F, to engage with pawls G,

pivoted in the upper sides of said boxes, and operated by springs H, the object of which is to retain the end-gate in any position in which it may be placed when closed, or nearly so.

The lower ends of the straps or braces D are bent outward to form catches I, which abut against cross-pieces J in the boxes E when the end-gate is open, thus securing and supporting it in such position.

To the lower hinged end of the end-gate are secured lugs or studs K K, adapted to rest against the bottom of the wagon-box when the end-gate is open, thus giving it greatly-increased strength and supporting capacity.

The operation and advantages of my invention will be readily understood from the foregoing description, and by reference to the drawings hereto annexed. It is simple, durable, and very strong.

Having thus described my invention, I claim and desire to secure by Letters Patent of the United States—

The wagon-box A, having boxes E, with cross-pieces J, in combination with the hinged end-gate B, having segmental straps or braces D, provided with bent or hooked ends I, as set forth.

In testimony that I claim the foregoing as my own I have hereto affixed my signature in presence of two witnesses.

WILLIAM ALCORN.
